UNITED STATES PATENT OFFICE

CARL FLAMM, OF NUERMBERG, GERMANY, ASSIGNOR TO ENN-WERKE NEU & NEU-BURGER, OF NUERMBERG, GERMANY, A COMPANY OF GERMANY

ELECTRIC TORCH

Application filed October 18, 1927, Serial No. 226,934, and in Germany November 27, 1926.

This invention relates to an improved electric torch of the kind in which the lamp and its reflector are relatively adjustable in the direction of the optical axis of the reflector by means of a hand-operated device projecting through the casing and guided therein.

One object of the invention is to provide a simple construction adapted for ensuring maximum reliability in use.

10 A further object of the invention is to provide a slider which is guided in the casing and supports the lamp socket and a contact device the latter being adapted for slidably engaging a fixed contact device and thereby 15 maintaining a closed lamp circuit in various positions to which the lamp may be adjusted.

A further object of the invention is to adapt the arrangement of contact devices so that the switching on and off of the lamp may 20 be performed automatically by the parts when shifted by the hand adjustment which alters the relation between the lamp and its reflector.

A further object of the invention is to provide advantageous lamp switch devices which 25 can be operated from the exterior of the torch and by the same hand as that which carries the torch and effects the adjustment of the lamp in relation to its reflector.

Yet another object of the invention is to 30 adapt the improved switching and adjustment devices whereby they are under the operative influence of one finger or thumb of the hand which grasps the torch.

These and other objects will be made clear 35 by the aid of descriptions of examples of suitable constructions illustrated in the annexed drawings forming part of this specification, wherein:—

40 Figure 1 is partly a central longitudinal section and partly an elevation of a torch constructed in accordance with the invention.

Figure 2 is a sectional view of a fragment 45 of the casing and lamp adjusting means guided therein, the plane of this section being at right angles to the plane of the section in Figure 1.

Figures 3 and 4 are views similar to Figure 1 but illustrating modified constructions, and 50 Figure 5 is an elevation of switch and ad-

justment devices as viewed from the right hand side of Figure 4.

In Figure 1, the usual torch casing *a* encloses a battery *g* which is retained in position by a screw cap on the lower end, this cap having the usual spring device for pressing the battery *g* upwardly. The lower portion of the casing *a* is fitted with a pivoted and foldable suspension loop *f*, if desired.

In the upper part of the casing *a* there is fixed an annular diaphragm or partition *b*, and the upper end of the casing is closed by the usual glass or lens *c* carried by the screw cap *d*. The reflector *e* is secured by the screwing on of the cap *d*.

An annulus *h* of insulating material is fixed to the partition *b* and a disc of conductive metal *i* is secured in the insulating ring *h*. The central pole *k* of the battery is pressed against the disc *i*.

A conductive spring *l* connects the disc *i* with a contact stud *m* which is mounted on a cylindrical slider *n* situated within the casing above the partition *b*. If the slider *n* is of metal, the stud *m* is insulated from it as shown. On the top of the slider *n* there is mounted a socket *o* to receive the screw plug *p* of the lamp *q*. Between the slider *n* and socket *o* there is interposed a contact blade or arm *r*, this latter being insulated from the slider *n* and stud *m* by the same insulation as that which serves for insulating the stud *m*. The blade or arm *r*, however, is in electrical contact with the socket *o*, the latter being in similar contact with the usual terminal cap of the lamp plug. When the lamp *q* is screwed in, its other terminal *s*, which is centrally disposed in the end of the screw plug, makes contact with the stud *m*.

The outer end of the blade or arm *r*, which may be bent at a right angle as shown, makes a sliding contact with a contact blade or bar *t*, the latter being mounted upon the inner surface of the casing and insulated from the latter by the insulation strips *u*. A pressure knob *v* is carried by a blade spring fixed to the casing *a* and when this knob is pressed inwards against the action of its spring, it makes contact with the blade or bar *t* and

so completes the lamp circuit through the battery.

The slider *n* is fitted with an external knob *w* the stem of which extends through a longitudinal slot *x* in the casing *a*, as seen clearly in Figure 2. The knob *w* is conveniently disposed about 90° around the casing from the switch knob *v*. It will now be seen that the slider *n* and with it the lamp *q* mounted thereon may be shifted to and fro within the casing *a* in the direction of the optical axis of the reflector *e*, thereby altering the focus or relation between the lamp and reflector. As the slider *n* and lamp *q* are adjusted to and fro, the socket *o* slides in a sleeve extension of the reflector *e*. Also the spring *l* will elongate or contract in accordance with the movement of the slider *n*. In any position to which the lamp may be adjusted, the contact arm *r* will maintain contact with the blade *t*, so that the continuity of the lamp circuit will be preserved so long as the switch *v* is closed. Owing to the friction between the sliding surfaces, the slider *n* and lamp *q* will remain in any position to which they may be adjusted.

It will be understood, by comparing Figures 1 and 2, that the torch may be operated by one hand as the first finger of the right hand, for example, may be applied to the knob *w* for the adjustment of the slider *n* and lamp *q*, whilst the thumb may be applied to the press knob *v* for switching the lamp on. Also the switch may be closed and retained in the closed position by moving the slider *y* upwards by pressure of the thumb, the knob *v* being then engaged and depressed by the slider.

According to the modification illustrated in Figure 3, the thumb-operated switch is dispensed with and the switching is performed automatically when moving the slider to adjust the focus. The construction generally of the modification is similar to that described with reference to Figures 1 and 2, the central terminal *k* of the battery being in contact with an insulated metal disc *i* which is electrically connected by a spring *l* with the insulated contact stud *m* and the latter being engaged by the central terminal contact of the lamp plug when screwed into the socket. The metal arm *r* interposed between the lamp socket and the slider *n* makes electrical contact with the metal of the socket but is insulated from the slider *n*, as in Figure 1. In this modification, however, the outer end of the arm *r* is perforated or slotted to embrace, or take over, a vertical contact bar or blade *t* fixed to the metal casing *a* and in electrical connection therewith. The bar *t* is insulated against the arm *r* by insulation *u*. Near the outer end of the arm *r* there is mounted a spring contact *3* which is adapted for pressing against the insulation *u* or against the contact bar *t* according to the position to which the slider *n* is adjusted. When the

slider *n* is adjusted to its lowest position by the knob *w*, which is the position of the parts in Figure 3, the spring contact *3* presses against the insulation *u* and the lamp circuit is broken. Upon moving the slider *n* upwards and thereby adjusting the lamp bulb outwards or away from the reflector, the spring contact *3* comes on to the metal of the contact bar *t* and completes the lamp circuit. In the Figure 3, the spring contact *3* is bent to form a nose and the bar *t* is fitted with a projection or facing strip for the nose to bear upon, so that good contact will be secured. The spring contact *3* closes the lamp circuit immediately the outward movement of the slider commences and maintains closure of such circuit throughout the range of adjustment of the slider *n* and the lamp bulb carried thereon. The lamp circuit is broken upon again restoring the parts to the position seen in Figure 3.

The further modification illustrated in Figures 4 and 5, whilst embodying the arm *r* and spring contact *3* described with reference to Figure 3, does not embody the feature of automatic switching. The contact *3* continuously presses against the metal of the contact bar or blade *t* which is insulated from the casing *a* as in Figure 1. In this further modification, the slider *n* receives guidance from a slider plate *4* which slides in a groove formed in an extension of the switch housing *5*, the stem of the knob *w* which is connected with the slider *n* being passed through a perforation in the slider plate *4* and through a slot in the casing *a*. The contact bar or blade *t* passes through an opening *z* in the slider *n* as well as through a slot or perforation in the end of the arm *r*. The lower end of the bar or blade *t* is bent to pass through an opening in the casing *a* and to present a contact point for engagement by the press knob *v* when depressed. The knob *v* is carried by a blade spring *1* which is fixed in the metal switch housing *5*, the latter being riveted to the casing *a*. The blade spring *1* is bent so as to present an incline suitable for engagement by a tooth or projection *6* on the slider *y*, the latter being movable up or down by thumb or finger pressure and guided in a slot in the housing *5*. Thus, the lamp can be adjusted in relation to the reflector by means of the knob *w* and the lamp circuit can be closed by pressing the knob *v* into contact with the bar *t*. Also the lamp circuit can be closed and maintained in the closed condition by moving the slider *y* upwards, whereupon the projection *6* engages the incline of the blade spring *1* and flexes the latter so that the knob *v* is mechanically pressed against the contact point of the bar *t*.

As will be seen from Figure 5, the knobs *w*, *v* and *y* are all in alignment and this arrangement enables all knobs to be operated.

with great ease whilst the torch rests securely in the hand of the operator.

I claim:

In an electric torch with unitary switch and focus adjustment and in which the torch casing is included in the circuit, a lamp carrier whose outer diameter is equal to the inner diameter of the casing axially slideable with guidance within the torch casing and fitted with insulated lamp contacts, an extensible connection between one battery terminal and one of said contacts, a contact slide connected with the torch casing, a contact arm connected with the other of said lamp contacts and having sliding engagement with the contact slide, and an insulated covering for said slide, said covering limiting the range of sliding contact and causing a break in the lamp circuit when said range is exceeded, substantially as set forth.

CARL FLAMM.
